(57) **CLAIM**

The ornamental design for a gear housing assembly, as shown and described.

DESCRIPTION

FIG. 1 is a perspective view of an embodiment showing our new design configured solely as a gear housing assembly with the mounting structure, input shaft structure and output shaft shown in dotted line;

FIG. 2 is a top view thereof;

FIG. 3 is a front view thereof;

FIG. 4 is a back view thereof;

FIG. 5 is a left side view thereof;

FIG. 6 is a right side view thereof; and,

FIG. 7 is a bottom view thereof.

The items shown in broken lines in the various views of the Figures do not form a part of our inventive design and are not claimed herein.
